UNITED STATES PATENT OFFICE

172,337

PHOTOMETER

Frank F. Crandell, Pasadena, Calif., assignor to
Photo Research Corporation, Burbank, Calif.,
a corporation of California

Application February 16, 1953, Serial No. 23,648

Term of patent 14 years

(CL. D61—1)

To all whom it may concern:

Be it known that I, Frank F. Crandell, a citizen of the United States, residing at Pasadena, county of Los Angeles, and State of California, have invented a new, original, and ornamental Design for a Photometer, of which the following is a specification, reference being had to the accompanying drawing, forming a part hereof.

Fig. 1 is a front perspective view of a photometer showing my new design; and Fig. 2 is a rear perspective view thereof.

I claim:

The ornamental design for a photometer, substantially as shown.
